UNITED STATES PATENT OFFICE.

OTIS A. MYGATT, OF NEW YORK, N. Y.

DESIGN FOR AN ILLUMINATOR.

No. 37,824.

Specification for Design.

Patented Feb. 13, 1906.

Application filed July 14, 1905. Serial No. 269,732. Term of patent 14 years.

To all whom it may concern:

Be it known that I, OTIS A. MYGATT, a citizen of the United States, residing at New York, in the county of New York and State of New York, have invented a certain new, original, and ornamental Design for Illuminators, of which the following is a specification, reference being had to the accompanying drawings, forming part thereof.

This design is for an electrical illuminator.

Figure 1 is a side elevation of the illuminator. Fig. 2 is a lower side perspective of the same.

The socket or holder of the illuminator is of opaque material. The bell is of transparent glass. The lower or visible end of the bulb is of frosted glass.

I claim—

The ornamental design for an illuminator as shown and described.

OTIS A. MYGATT.
